UNITED STATES PATENT OFFICE

2,138,587

APPARATUS FOR MAKING SANITARY
NAPKINS

Oscar T. Thompson, Neenah, Wis., assignor to International Cellucotton Products Company, Chicago, Ill., a corporation of Delaware

Application May 3, 1937, Serial No. 140,278

8 Claims. (Cl. 154—29)

This invention relates to apparatus for making an improved sanitary napkin.

The main object of the invention is to provide mechanism of simple, durable and reliable character for making an improved sanitary napkin, the improvement particularly contemplating the production of sanitary napkins with absorbent pads having marginal side portions compressed so as to more or less round the side edges to reduce bulkiness adjacent the side edges; and to provide mechanism for producing sanitary napkins embodying the improved construction.

Other objects of the invention are to provide a pad side margin compressing device of simple construction but which is efficient in operation; to provide such compressing means which will not show up the operation of the apparatus; to provide such means which may be readily added to sanitary napkin making machines already in use; and in general, it is the object of the invention to provide an improved sanitary napkin making mechanism of the character indicated.

Other objects and advantages of the invention will be understood by reference to the following specification and accompanying drawing, wherein there is illustrated a sanitary napkin embodying the construction herein contemplated and also mechanism for producing the same.

In the drawing:

Fig. 1 is a plan showing a portion of a sanitary napkin making machine, the portion being that part which compresses the marginal side portions of the absorbent pad elements and folds a gauze strip around the pads.

Fig. 2 is a side elevation of the mechanism shown in Fig. 1.

Figs. 3 and 4 are sections, respectively, on lines 3—3 and 4—4 of Fig. 1.

Fig. 5 is a section similar to Fig. 3, but showing relationship of the parts of the mechanism to the parts of the sanitary napkin and the effect of the mechanism on the absorbent pad element, and

Fig. 6 is a cross section through a sanitary napkin embodying the improved construction.

The mechanism illustrated in Figs. 1 and 2 is similar to the pad-wrapping mechanism shown in the patent to Fourness No. 2,052,529, issued August 25, 1936. It comprises a table or support 10 over which travels a conveyor belt 11. The conveyor belt 11 extends around a guide roller 12 journaled in any suitable manner but not herein illustrated. The belt 11 is a continuous belt which also extends around another guiding

roll as will be readily understood by those skilled in the art.

A strip of gauze designated 13 is fed over the roller 12 and the conveyor belt 11 and is thereby conveyed along the table 10. By suitable means such as shown in said Fourness patent, pad units designated 14 are deposited on the gauze strip in regularly spaced relation lengthwise of the gauze strip.

During the forward movement of the gauze strip and pads, the side marginal portions of the gauze strip which extend beyond the side edges of the pad units 14 are acted upon by folding devices 15 and 16 which fold said marginal gauze portions upwardly and inwardly over the absorbent pad units. Pad edge covering strips such as indicated at 17 which are preliminarily deposited upon the gauze in proper position relative to the pads are also folded around the side edges of the absorbent pad units as an incident to the folding of the gauze.

To reduce the thickness of the absorbent pad, and also of the finished sanitary napkin, the marginal side portions of the pads may be compressed. Such compressing may be effected by means of an elongated presser plate 18, preferably made of metal and supported at one end on a rod 19 which is carried by a bracket 20 fastened to the table 10 so as to clear the gauze strip 13. As clearly shown in Figs. 1 and 2, the rod 19 is vertically adjustable in the bracket 20, the rod being clamped in the desired position by means of suitable clamping nuts as indicated. The presser plate 18 has a reduced end portion 21 bent around the rod 19 so that the presser plate is, in effect, pivotally supported by the rod 19. Cotter pins or the like indicated at 22 may be employed for holding the presser plate 18 against sidewise shifting on the rod 19. As clearly indicated, the pivotally supported or receiving end of the presser plate 18 is offset upwardly so as to provide a flared mouth into which the pad elements will enter. The marginal side portions 23, 23 of the presser plate are offset downwardly as best shown in Fig. 3, so that the underlying marginal portions of the absorbent pads will be correspondingly compressed (see Fig. 5). By reason of the flared mouth construction of the presser plate, the compression of the marginal portions of the pads will be effected more or less gradually as the pad advances under the pressing plate and into the zone of operation of the gauze folding devices 15 and 16.

The delivery end of the presser plate 18 has one side tapered as indicated at 24 so as to be 55

substantially parallel with the inner edge of the folder 15, and so that the presser plate does not project materially under said folder. The extreme end portion 18^a of the presser plate represents about one-half of the normal width of the presser plate and has one corner portion 18^b projected under the folder 15.

The free or delivery end of the presser plate 18 is supported by means of a spring blade 25 which is secured at one end of a rod 26 which is adjustably mounted in a bracket 27 carried by the table 10. The other end of the spring member 25 is secured to the delivery end of the presser plate by welding or otherwise as preferred. It will be apparent that the spring member 25 will yieldingly and resiliently support the free end of the presser plate. For facilitating variation of the pressure of the pressing plate on the pad element passing thereunder, the presser plate may be provided with an upstanding post designated 28 for receiving one or more weights 29 which may be readily slipped on or off the post 28. By varying the number of the weights 29, the pressing effect of the presser plate on the absorbent pads may be varied to meet varying requirements and possibly to compensate for variations in the character of the pad material.

By pressing the pads as indicated, the thickness of the pad edges is reduced relative to the thickness of the pads intermediate said edges. The effect of the pressing is illustrated in Fig. 6, where the pad edges designated 30, 30 are shown as being of less thickness than the intermediate 35 portions of the pad. The gauze wrapper 13 around the pad may thus be somewhat narrower than the gauze wrapper required where the pads are of uniform thickness over their entire width. Similarly, the width of the pad edge elements 40 17, 17 may be reduced somewhat from the width required where the pad thickness is uniform from edge to edge. In addition to the indicated reduction in bulk with consequent comfort-giving effects, there is an important saving effected in the 45 cost of material incident to the reduced width requirements of the latter as explained.

The slight compressing effect is also desirable in that when the pad is made of a multiplicity of superposed plies of creped tissue paper as 50 herein contemplated, there is a definite tendency for the plies to be more effectively united along said compressed edges to thereby avoid splitting of the absorbent pad unit. The extent of compression is, however, such that it does not produce a material hardening effect which would be seriously objectionable. The effect of the compressing operation appears to be that of eliminating bulkiness with consequent comfort advantages and without noticeably hardening any portion 55 of the pad or reducing its absorbent capacity. Owing to the normal tendency of the compressed material to expand to normal incompressed condition, there is a tendency for the gauze wrapped around the pad to be automatically drawn taut. Such 60 tendency results in a smoothly wrapped napkin and the gauze serves, of course, to prevent expansion of the compacted marginal portions beyond certain limits. In other words, the gauze has the effect of maintaining the marginal 65 portions compressed.

The described pad pressing arrangement may be added to apparatus such as shown in the aforesaid Fourness patent, and it will be apparent that the pressing apparatus does not slow up 70 or otherwise impair the operation of the machine.

Changes in the described structure may be made without departing from the spirit of the invention, the scope of which should be determined by reference to the following claims, the same being construed as broadly as possible consistent with the state of the art.

I claim:

1. In a machine for making sanitary napkins, means for conveying a strip of gauze having an absorbent pad positioned thereon, the pad being narrower than said gauze strip and being positioned in spaced relation to the side edges of said strip, means for folding the marginal portions of said strip upwardly and over the pad and means associated with said gauze folding means for acting on said pad while being conveyed by said gauze strip to compress marginal side portions of the pad so as to reduce the thickness thereof at its side edges, whereby said side edges require less gauze or other covering material 20 and permit adequate wrapping of the pad and covering of its edges with covering material of reduced width.

2. In a machine for making sanitary napkins, means for conveying a strip of gauze having an absorbent pad positioned thereon, the pad being narrower than said gauze strip and being positioned in spaced relation to the side edges of said strip, means for folding the marginal portions of said strip upwardly and over the pad and a presser plate bearing on said pads and having marginal portions offset downwardly so as to compress marginal portions of the pad as an incident to the travel of the pad under said plate.

3. In a machine for making sanitary napkins, means for propelling absorbent pads, a presser plate acting on marginal portions of said pads for compressing said marginal portions, and means for yieldingly urging said presser plate 40 into engagement with the pads.

4. In a machine for making sanitary napkins, means for propelling absorbent pads, an elongated presser plate having marginal portions offset downwardly, said plate overlying the path 45 of travel of the pads and said offset plate portions being adapted to compress marginal side portions of the pads as an incident to the movement of the latter under said presser plate.

5. In a machine for making sanitary napkins, means for propelling absorbent pads, an elongated presser plate having marginal portions offset downwardly, said plate overlying the path 50 of travel of the pads and said offset plate portions being adapted to compress marginal side portions of the pads as an incident to the movement of the latter under said presser plate, said presser plate being pivotally supported adjacent one end and having resilient supporting means adjacent its other end.

6. In a machine for making sanitary napkins, means for propelling absorbent pads, an elongated presser plate having marginal portions offset downwardly, said plate overlying the path 65 of travel of the pads and said offset plate portions being adapted to compress marginal side portions of the pads as an incident to the movement of the latter under said presser plate, means for adjustably supporting said presser plate adjacent one end, and variable pressure means acting on the other end of the plate for controlling the pressing effect of the plate on the pads.

7. In a machine for making sanitary napkins, means for propelling absorbent pads, an elongated presser plate having marginal portions off- 75

set downwardly, and means for positioning said presser plate in longitudinally overlying relation to the path of travel of the pads, said plate being shaped to provide a flaring mouth portion to facilitate the entrance of pads into their path of travel under said plate, said offset plate portions serving to compress marginal side portions of the pads as an incident to their travel under said presser plate.

10 8. In a machine for making sanitary napkins, means for propelling absorbent pads, an elongated presser plate having marginal portions off-

set downwardly, said plate overlying the path of travel of the pads, and means for pivotally supporting said presser plate adjacent the pad-receiving end thereof, the receiving end portion of said plate being shaped longitudinally to provide a flaring mouth portion to facilitate the entrance of pads into their path of travel under said plate, said offset marginal plate portions serving to compress marginal side portions of the pads as an incident to their travel under said presser plate. 5

OSCAR T. THOMPSON.
